WASHING MACHINE AND ROLLER DRIVE MECHANISM THEREFOR

Donald A. Brackman and Byron L. Brucken, Dayton, Ohio, assignors to General Motors Corporation, Detroit, Mich., a corporation of Delaware

Filed Feb. 4, 1965, Ser. No. 430,265
16 Claims. (Cl. 68—23)

This invention relates to a domestic appliance and more particularly to an improved roller drive mechanism for agitating and spinning in a clothes washer.

Roller drive mechanisms, such as taught in the patent to Brucken 3,087,321, issued April 30, 1963, use certain self-energizing rollers as idlers members between the motor and the driven member for producing either agitate or spin. Such roller drive mechanisms may include a reversible motor, the reversibility of which determines whether agitate or spin is produced. Each of the rollers is provided with a resilient tire portion of polyurethane or the like as the motion transmitting surface. During agitation, one of the rollers is in power transmitting relationship while the other roller is overridden and merely idles. During the life of the roller, therefore, the tire portion may wear unevenly due to the scuffing action on the tire surface of the roller not transmitting power. This scuffing action tends to form an undulated or washboard-like surface on the roller tire. When this wear phenomenon occurs, a smooth driving connection is lacking between the drive motor and the driven member with the result that the mechanism becomes noisy due to the added vibration in the system.

Accordingly, it is an object of this invention to provide in a roller drive mechanism means for preventing scuffing action on the surface of the roller tires in the driving train.

More particularly, it is an object of this invention to provide a roller retraction device for a roller drive mechanism which selectively withdraws rollers not being used to transmit power.

A further object of this invention is to provide a roller drive mechanism with means responsive to the direction of motor rotation for retracting the self-energizing roller not then in the driving train with the motor.

Further objects and advantages of the present invention will be apparent from the following description, reference being had to the accompanying drawings wherein a preferred embodiment of the present invention is clearly shown.

In the drawings:

FIGURE 1 is a schematic sectional view, partly in elevation, of a clothes washer provided with the improved roller drive mechanism of this invention;

FIGURE 2 is a fragmentary sectional view, partly in elevation, of the self-energizing rollers in relationship to the drive motor and illustrating one of the rollers therein as having the roller retraction device of this invention;

roller drive agitating and spinning mechanism of this invention;

FIGURE 11 is a diagrammatic showing of the roller retractor device during the agitate operation of the roller drive mechanism; and

FIGURE 12 is a diagrammatic showing of the roller retractor device during the spin operation of the roller drive mechanism.

For use with this invention and with reference to FIGURE 1, a clothes washer 20 is comprised of a control housing assembly 22 and a casing 24. The casing 24 is generally divided into a mechanism portion or compartment 26 and a washing compartment or water container chamber 28. A generally centrally located bulkhead 30 separates the mechanism compartment 26 from the water container chamber 28 which is further bounded by a cylindrical water container wall 32. Within the water container 32 is a spin tub 34 having a top opening 36 and a plurality of centrifuging outflow ports 38. The ports 38 are designed to permit the egress of water from the tub 34 when the tub is rotated at high speed. For filling the tub 34 with water a conventional water supply system may be provided with a hot and cold water solenoid operated mixing valve 42 which is manifolded into a mixed water supply conduit 44 terminating at a chute overlying the opening 36 of the tub. Within the tub 34, an agitator or pulsator 48 is adapted to reciprocate vertically to circulate or agitate the water admitted through the water supply conduit 44. Thus, clothing placed within the tub 34 is washed as the agitating action of the pulsator 48 forces surging toroidal currents of washing fluid and detergent through the fabric. Conventional sequential operating timer means, shown generally at 50 on the control housing 22, may be included selectively to admit water through the supply conduit 44, to spin the tub 34 and to vertically reciprocate the agitator or pulsator 48.

Roller drive mechanisms for selectively spinning a tub and reciprocating or oscillating an agitator are taught in the aforementioned Brucken patent, in Sisson Patents 3,060,712 issued October 30, 1962, and 3,165,911 issued January 19, 1965, and in copending application Serial No. 128,074 filed July 31, 1961, now Patent No. 3,174,596, and assigned to the same assignee as this invention. This invention is directed to a roller retractor device for use in combination with these roller drive mechanisms, one of which is shown generally at 51 in FIGURE 1, said device providing for removal of the roller not driving, in response to the direction of motor rotation, thereby eliminating tire wear due to scuffing of the tread thereof.

FIGURE 2 is a fragmentary sectional view, partly in elevation, of the self-energizing rollers in relationship to the drive motor and illustrating one of the rollers therein as having the roller retraction device of this invention;

FIGURE 3 is a top elevational view of the roller retractor assembly;

FIGURE 5 is a fragmentary sectional view similar to FIGURE 3 taken along line 5—5 in FIGURE 8;

FIGURE 6 is a perspective view of the roller retractor assembly;

FIGURE 7 is an exploded perspective view of the link portions of the roller retractor assembly;

FIGURE 8 is a side elevational view of the roller retractor assembly;

FIGURE 9 is a sectional view taken along line 9—9 in FIGURE 8;

FIGURE 10 is a perspective view of the improved

turning now to FIGURE 10, the agitating and spinning mechanism 51 will now be described more particularly.

The mechanism includes a $\frac{1}{3}$ h.p., split phase, single speed 1725 r.p.m., four-pole reversible motor 60 with a built-in automatic reset type thermal overload protector. The motor 60 has a depending power shaft 62 having a spin portion 64 and a reduced diameter agitate portion 66 keyed thereto.

On the same general plane as the spin drive portion 64 is a spin wheel assembly or spin driven roller means 68 of the type taught in the concurrently filed application Serial No. 430,264 while an agitate wheel or agitate driven

roller means 70 lies in the same plane as the agitate drive member 66. Interposed between the agitate drive portion 66 and the agitate wheel 70 is the agitate roller or idler 72, spring loaded and laterally floating to make it self energizing according to the concept of the Brucken patent. Similarly, a self-energizing spin roller or idler 76 lies between the spin drive portion 64 and the spin wheel assembly 68.

In general, the operation of the motor 60 in the direction of the arrows shown in FIGURES 10 and 11 will drive the agitate wheel 70 through the agitate roller 72—this driving motion being translated into reciprocation through the rocker arm assembly 78. Conversely, with the motor 60 reversed from the operation shown by the arrows in FIGURE 10, as in FIGURE 12, the roller 76 will be drawn into a wedging driving connection between the spin drive member 64 and the spin wheel 68 to rotate the spin tub 34.

In roller drive mechanisms having a single agitate speed and a single spin speed, the so-called two-speed mechanism of the aforementioned Brucken patent, one roller, due to overrunning, would be caused to scuff against the surface of its respective wheel while the other roller was in the power train transmitting the driving force. This scuffing action may create wear problems on the surface of the tire of the non-driving roller. In this invention a roller retractor device shown generally at 80 solves the problem by automatically withdrawing the non-driving roller from scuffing engagement with its respective driven wheel whenever the roller is being overrun or rotated in a direction tending to remove the roller from its wedging engagement between the powershaft and the driven wheel.

At this point, it should be noted that the retractor device 80 is shown only on the spin roller 76 although it could as well be used with the agitate roller 72. It is not thus used for the reason that the rubbing or scuffing action of the agitate roller 72 against the agitate wheel 70, during spin, is insignificant due to the small diameter of the agitate driver 66.

Turning now to FIGURES 2-9, the roller retractor assembly 80 will now be described. The assembly is comprised of the spin roller 76 having a polyurethane tire 81 molded onto an aluminum die cast insert 83. A sintered bronze bushing 85 is pressed into the insert to form a hub for the roller.

For supporting the roller 76 the retractor assembly includes a U-shaped support bracket 84 having an upper support arm 86 and lower support arm 88 held apart at their terminal ends by a spool-like spacer sleeve 90. Sandwiched between the arms 86, 88 are a pair of pivot arms or links 92, 94, an upper pivot arm 92 having a socket portion 96 for rotatably journaling the upper end 98 of the bushing 85 while the socket portion 100 of the lower pivot arm journals the lower end 102 of the bushing. The diameter of the bushing 85 is oversized relative to the spacer sleeve 90 to provide a sloppy fit. In view thereof the socket portions of the pivot arms as well as the roller 76 journaled therein are permitted to shift in all lateral directions around the spacer sleeve.

Between the other ends of the pivot arms 92, 94 is a sintered brass retractor roller 104, the bearing sleeve 105 of which is journaled on a shaft 106 which extends through elongated slots 108, 110 in the upper and lower bracket forms 86, 88, respectively. The upper and lower pivot arms also have elongated slots 114, 116, respectively, to permit restricted, generally radial lateral movement of the retractor roller 104 toward and away from the spin roller 76. A leaf spring 120 circumscribes the closed end of the support bracket 84 and is attached thereto at 122, the ends of the spring engaging the grooves 119, 121 in the terminal portions 124, 126 of the shaft 106 to bias the retractor roller within the limits of the pivot arm slots 114, 116 into engagement with the spin roller 76, thereby

5 to bias the spin roller and its bushing 85 toward the spacer sleeve 90, i.e., to make the roller self-energizing. A helper leaf spring 130 is attached to the inside of the support bracket at 122 and extends into biasing engagement with the inner ends of the upper and lower pivot arms 92, 94 to assist the spring 120 in making the spin roller self-energizing and to prevent rattling of the retractor assembly during operation.

10 The retractor roller 104 is thus spring biasingly forced against the surface of the spin roller 76 at a small angle A (FIGURE 12) from the centerline between the spin driver and the spin roller, say 20° although this angle will vary with roller drive mechanisms having different diameter rollers. In general the retractor assembly should be 15 affixed to the motor end frame in a manner, during standstill, to cause the spin roller to engage both the spin driver 64 and the spin wheel 68, but in a manner and at such an angle during agitate operation (FIGURE 11), the drag of the retractor roller 104 in conjunction with the driving force between the spin driver and spin roller will tend to cause the spin roller to wedgingly drive between the retractor roller and the spin driver and away from the stationary spin wheel 68. As the spin roller retracts, the pivot arms on which it is journaled pivot about their integral arcuate 20 bosses, such as 150, 152 on the upper pivot arm 92. The retraction is limited when the hub 85 of the spin roller engages the spacer sleeve 90. At this point the spin roller and retractor roller will merely idle out of scuffing engagement with the spin wheel. When the agitate operation 25 ceases, the spring bias of the retractor roller will return the spin roller to a position in engagement with both the spin driver and the spin wheel—ready, self-energizingly, for any subsequent spin operation.

30 More particularly and with reference to FIGURE 2, the retractor assembly 80 is attached to the lower end frame 134 of the motor by a bolt 136 which extends through the spacer sleeve 90 of the roller 76 and threadedly engages the motor end frame to hold the retractor assembly adjacent thereto. A tang 138 struck upwardly 35 from the support bracket arm 86 extends into a hole 140 in the motor end frame to position the retractor assembly relative to the spin driver 64 and spin wheel 68 in the manner described immediately hereinabove.

40 Arcuate bosses, such as 150 and 152, on the upper pivot arm 92 are raised from the surface of both pivot arms 92 and 94 and extend through the respective slots 108 and 110 in the support bracket to provide the pivot point about which the pivot arms move when the spin roller 76 retracts.

45 The operation of the roller retractor device 80 is best understood with reference to FIGURES 11 and 12. The purpose of the device is to eliminate the wear on the tire-surface of the spin roller 76 by eliminating the scuffing action of the roller 76 against the wheel 68 which would occur in an overrunning relationship therewith. In the arrangement of this invention, the retraction is accomplished when the agitate roller is driving.

50 With reference in particular to FIGURE 12, a spin operation is schematically illustrated when the spin drive portion 64 of the motor shaft 66 drives the spin roller 76, spring biased for self-energization, into a wedging, power transmitting engagement between itself and the spin wheel 68, thereby to rotate the spin wheel and, thus, the spin tub 34 thereabove. For spin, the motor shaft rotates counter-clockwise. The spin driver 64, being keyed to the motor shaft, drives the spin roller 76. The spin roller is pushed into light contact with both the spin driver and the spin wheel 68 by the spring loaded retractor roller 104. As the motor starts to rotate the floating action of the spin roller on its spacer permits the roller to be pulled by rotational force into positive contact with the surfaces of the spin driver and the spin wheel. Thus, the rotational torque of the motor is transmitted through the spin roller to cause the spin wheel to rotate counter-clockwise.

During spin note that the agitate roller 72, since it is made self-energizing by the biasing effect of the springs 146, 148 on its oversize hub 151, is rotated by the agitate driver portion 66. However, the diameter of the agitate driver 66 is small compared with the spin driver 64 and the small amount of scuffing or overrunning action between the agitate roller 72 and the agitate wheel 70 is negligible and the retraction of the roller 72 unnecessary.

When the motor 60 is reversed to condition the agitating and spinning mechanism 51 for agitate operation (FIGURE 11), the driving train is from the agitate drive member 66, the agitate roller 72 and the agitate wheel 70. In this situation, however, the relatively large diameter of the spin drive member 64 would cause a considerable scuffing action between the mating surfaces of the spin roller 76 and the spin wheel 68. Thus, the roller retractor device 80 acts to remove the roller 76 from scuffing relationship with the spin wheel.

It should now be seen that an improved roller drive mechanism has been provided wherein the scuffing action of the roller tires in a self-energizing roller drive mechanism is overcome by retracting the offending roller automatically to a position which will prevent scuffing and in response to the direction of motor rotation.

While the embodiment of the present invention as herein disclosed constitutes a preferred form, it is to be understood that other forms might be adopted.

What is claimed is as follows:

1. In combination, a washing machine having a tub, an agitator in said tub, and a roller drive mechanism for reciprocating said agitator and rotating said tub, said mechanism comprising

- (a) support means,
- (b) a reversible motor,
- (c) an agitate shaft supporting said agitator on an upper end thereof,
- (d) a rotatable spin shaft drivably connected to said tub,
- (e) a shaft housing affixed to carry said support means and at least partially enclosing said agitate shaft and said spin shaft,
- (f) an agitate driven wheel rotatably supported by said support means,
- (g) said agitate driven wheel having an angularly directed crank portion,
- (h) an agitate arm assembly having a rocking end universally movably connected to said agitate shaft and a crank end relatively rotatably connected to said crank portion,
- (i) a spin driven wheel drivably connected to said spin shaft and coaxial therewith,
- (j) power shaft means drivably connected to said motor and having a power shaft agitate portion adjacent said agitate driven wheel and a power shaft spin portion adjacent said spin driven wheel, and
- (k) an agitate idler roller and a spin idler roller rotatably and spring-biasedly, relatively laterally movably supported by said support means adjacent said power shaft agitate portion and said power shaft spin portion respectively for self-energizingly positioning themselves in power transmitting relationship between the respective power shaft agitate or spin portions and the respective agitate or spin wheels in accordance with the direction of motor operation,
- (l) one of said idler rollers being in spring-biased, non-driving engagement with its respective agitate or spin power shaft portion when the other of said idler rollers is in power transmitting relationship with its respective agitate or spin power shaft portion,
- (m) said one of said idler rollers having a resilient tire thereon normally subjected to irregular wear at the surface thereof due to scuffing engagement of

the roller tire with its respective agitate or spin wheel,

(n) and means for automatically retracting said one of said idler rollers from engagement with its respective agitate or spin wheel whenever the other of said idler rollers is in power transmitting relationship.

2. The combination of claim 1 wherein said retracting means includes a retractor roller engaging said one of said idler rollers for lateral and rotational movement therewith and having an axis parallel thereto, said retractor roller and said idler roller being biased toward the respective driven wheel and power shaft portion at a sufficient angle that the drag of the retractor roller in conjunction with the driving force between the said one of said idler rollers and its respective power shaft portion will tend to cause said idler roller to wedgingly drive between the retractor roller and the said power shaft portion and away from the respective driven wheel.

3. In a washing machine, spin tub means, agitator means in said spin tub means, means for rotatably supporting said spin tub means, motor means, power transmitting means drivingly connecting said motor means to said spin tub means for rotating said spin tub means and

20 to said agitator means for moving said agitator means, said power transmitting means comprising a plurality of motion transmitting roller means having different moment arms and at least some of said roller means being self-energizing, said power transmitting means being operable for selectively transmitting motion through different combinations of roller means to select predetermined different speed ratios between said motor means and said tub means or said agitator means, and means for retracting one of said motion transmitting roller 30 means from one combination of roller means in response to the selection of another combination of roller means for transmitting motion, whereby to prevent said one of said roller means for overrunningly scuffing the surface of another one of the roller means in said one combination of roller means.

4. The washing machine of claim 3 wherein said retracting means includes means engageable with said one of said motion transmitting roller means and draggingly reacting to the rotation thereof for causing said last named roller means to drive itself from said one combination of roller means.

5. In a washing machine, spin tub means including agitating means therein, means for rotatably supporting said spin tub means, motor means, power transmitting means drivingly connecting said motor means to said spin tub means for rotating said spin tub means and for moving said agitating means, said power transmitting means comprising a plurality of motion transmitting roller means having different moment arms and at least some of said roller means being self-energizing, said power transmitting means being operable for selectively transmitting motion through different combinations of roller means to select predetermined different speed ratios between said motor means and said tub means or said agitator means, and means for removing one of said motion transmitting roller means from one combination of roller means in response to the selection of another combination of roller means for transmitting motion, whereby to prevent said one of said roller means from overrunningly scuffing the surface of another one of the roller means in said one combination of roller means.

6. The washing machine of claim 5 wherein said motor means is reversible and the selection of a combination of roller means is dependent on direction of operation of said motor means.

7. The washing machine of claim 6 wherein said means for removing one of said motion transmitting roller means is responsive to the direction of operation of said motor means.

8. In a washing machine, spin tub means including agitating means therein, means for rotatably supporting said spin tub means, motor means, power transmitting means drivingly connecting said motor means to said spin tub means for rotating said spin tub means and for moving said agitating means, said power transmitting means comprising a plurality of motion transmitting roller means having different moment arms and at least some of said roller means being self-energizing, said power transmitting means being operable for selectively transmitting motion through different combinations of roller means to select predetermined different speed ratios between said motor means and said tub means or said agitator means, and means for retracting one of said motion transmitting roller means from one combination of roller means in response to the selection of another combination of roller means for transmitting motion, whereby to prevent said one of said roller means from overrunningly scuffing the surface of another one of the roller means in said one combination, said retracting means comprising retractor support means affixed adjacent said one combination of roller means, said retractor support means having spacer means and means forming a pivot point, pivot arm means having a journal portion journaling said one of said roller means and a slotted pivot portion, said one of said roller means having hub means larger in diameter than said spacer means and around said spacer means, a retractor roller journaled in the slot of said pivot portion with its axis parallel to said one of said roller means in a manner to facilitate limited movement toward and away from said one of said roller means, and means for biasing said retractor roller into engagement with said one of said roller means and for biasing said pivot arm means away from said support means and toward the said one combination of roller means, whereby the direction of rotation of said one of said roller means will determine the direction said pivot arm means will pivot about the pivot point in said retractor support means thereby to add said one of said roller means to said one combination of roller means or to retract said one of said roller means therefrom.

9. An agitating and spinning mechanism comprising, two shaft means concentrically arranged, support means for said shaft means, spin driven roller means drivably connected to one of said shaft means for rotating said one of said shaft means, means drivably connected to the other of said shaft means for motivating said other of said shaft means, agitate driven roller means rotatably carried by said support means for driving said motivating means, reversible power shaft means, first self-energizing roller means laterally movable with respect to said spin driven roller means and said power shaft means for selectively wedgingly engaging said spin driven roller means and said power shaft means to motion transmittingly connect said power shaft means with said spin driven roller means when said power shaft means is operating in one direction for inducing spinning, and second self-energizing roller means laterally movable with respect to said agitate driven roller means and said power shaft means for selectively wedgingly engaging said agitate driven roller means and said shaft means to motion transmittingly connect said power shaft means with said agitate driven roller means when said power shaft means is operating in the reverse direction for inducing agitating, one of said first or second self-energizing roller means including an idler roller and means for moving said idler roller out of wedging engagement with its respective driven roller means in response to the direction of operation of said power shaft means.

10. An agitating and spinning mechanism comprising, two shaft means concentrically arranged, support means for said shaft means, spin driven roller means drivably connected to one of said shaft means for rotating said one

of said shaft means, means drivably connected to the other of said shaft means for motivating said other of said shaft means, agitate driven roller means rotatably carried by said support means for driving said motivating means, power shaft means operable in a first and second manner, first self-energizing roller means movable with respect to said spin driven roller means and said power shaft means for selectively wedgingly engaging said spin driven roller means and said power shaft means to motion transmittingly connect said power shaft means with said spin driven roller means when said power shaft means is operating in a first manner for inducing spinning, and second self-energizing roller means movable with respect to said agitate driven roller means and said power shaft means for selectively wedgingly engaging said agitate driven roller means and said shaft means to motion transmittingly connect said power shaft means with said agitate driven roller means when said power shaft means is operating in a second manner for inducing agitating, one of said first or second self-energizing roller means including an idler roller and means for moving said idler roller out of wedging engagement with its respective driven roller means in response to the manner of operation of said power shaft means.

11. The agitating and spinning mechanism of claim 10 wherein said power shaft means includes a large diameter portion engaging said first self-energizing roller means and a small diameter portion engaging said second self-energizing roller means.

12. The agitating and spinning mechanism of claim 11 wherein said power shaft means is reversible.

13. The agitating and spinning mechanism of claim 12 wherein said means for moving said idler roller includes a retractor roller having an axis parallel to said idler roller and being spring biasingly, rollingly engageable with said idler roller.

14. The agitating and spinning mechanism of claim 13 wherein said idler roller has a polyurethane tire and said retractor roller is sintered brass.

15. A roller retractor assembly for a roller drive mechanism comprising support means adapted to be affixed adjacent a train of motion transmitting roller means, said support means having spacer means and means forming a pivot point, pivot arm means having a journal portion and a slotted pivot portion, an idler roller journaled in said journal portion and having hub means larger in diameter than said spacer means and around said spacer means, a retractor roller journaled in the slot of said pivot portion with its axis parallel to said idler roller in a manner to facilitate limited movement toward and away from said idler roller, and means for biasing said retractor roller into engagement with said idler roller and for biasing said pivot arm means away from said support means and adapted thereby for movement toward said train of motion transmitting roller means, whereby the direction of rotation of said idler will determine the direction said pivot arm means will pivot about the pivot point in said support means thereby to add the idler roller to said train of motion transmitting roller means or to retract said idler roller therefrom.

16. The retractor assembly of claim 15 wherein said idler roller has a polyurethane tire and said retractor roller is sintered brass.
